UNITED STATES PATENT OFFICE.

BENJAMIN F. MILLS, OF DECATUR, ILLINOIS.

LINE-CHALKER.

1,146,196.

Specification of Letters Patent. Patented July 13, 1915.

Continuation of application Serial No. 751,900, filed March 3, 1913. This application filed March 20, 1914.
Serial No. 826,017.

To all whom it may concern:

Be it known that I, BENJAMIN F. MILLS, a citizen of the United States, residing at Decatur, in the county of Macon and State 5 of Illinois, have invented certain new and useful Improvements in Line-Chalkers, of which the following is a specification.

This invention relates to an improvement in a device for chalking lines, as used by carpenters, gardeners and other artisans.

The principal object of this invention is the provision of such a device which is simple in construction, efficient in operation and easy to manipulate.

15 A further object of such an invention is the provision of such a device which is so constructed that it may run along on a guide line for chalking the same, the action being due to gravity.

20 A further object is the provision of such a device, including a handle portion which is weighted, a body portion provided with a chalk receptacle and having rollers mounted therein, with suitable apertures to provide a 25 passage for a line through the receptacle, and to permit the line to engage the rollers, whereby the device may move along the inclined line by gravity, chalk being applied thereto.

30 To the accomplishment of the foregoing and such other objects as may hereinafter appear, my invention consists in the construction, combination and arrangement of parts hereinafter described and then sought 35 to be defined in the appended claims, reference being had to the accompanying drawings forming a part hereof and which illustrate a preferred embodiment of my invention, it being understood however that various changes may be made in practice within 40 the scope of the claims without digressing from my inventive idea.

In the drawings:—Figure 1 is a side elevation of the device, one of the covers being 45 broken away and a line being shown in position for chalking. Fig. 2 is a front elevation thereof; Fig. 3 is an inside elevation of the plate or cover; Fig. 4 is a vertical section on line 4—4 of Fig. 1; Fig. 5 is an end 50 elevation of the device; Fig. 6 is a bottom elevation thereof, and Fig. 7 is a top plan view thereof.

Referring now to the drawings, the numeral 1 designates the handle portion which 55 is preferably formed solid to provide a

suitable weight, and the numeral 2 designates the body portion. This body portion is formed in two parts, one 3, being formed rigid with the handle, and the other 4, being in the form of a cap or plate. The 60 member 3 is provided with the peripheral flange 5, which flange however is reduced at the two lower corners thereof as indicated at 6 for a purpose to be described. Corresponding partition flanges 7 are provided on the member 3 between the peripheral flange on the top and on the bottom and also on the member 4. The space bounded by the partition flanges 7 on the side and the peripheral flange 5 on the top 70 and bottom provide a suitable receptacle for powdered chalk or a similar substance, said corresponding flanges being grooved as at 8 to provide the apertures 8' in their lower portions, as shown in Fig. 1. In the 75 small compartments 9 which are provided by the partition flanges 7 and the corner portions of the peripheral flanges 5, are provided the apertured studs or bosses 10. The cap or cover plate 4 corresponds in 80 shape and size to the body plate or member 3 having the apertured studs or bosses 11 corresponding to the studs 10 hereinbefore described, and having the flanges 12 at its lower corners corresponding to the reduced 85 flanges extending between the shoulder 6 and the ends of the partition flanges 7 on said body member 3. The peripheral flange 5 is cut away in its upper intermediate portion to provide the opening 13, in which 90 fits the door member 14 pivoted as at 14' to the member 3 and having the rear lug or extension 14'' against which the end of spring member 15 bears, said spring member being supported on the pin or lug 15' and normally holding the door member shut.

95 Suitable wheels or pulleys 16 are positioned between the apertured studs or bosses 10 and 11 and held in position by 100 means of the shafts or bolts 17. When the parts are in this position the flanges 12 do 105 not touch the reduced portions of the peripheral flanges 5, but leave a space 18 therebetween, which space is in substantial alignment with the center of the wheels or pulleys 16 so as to provide a slot or recess for the passage of the line. The body member 3 is grooved to provide recesses 19 for the string, and as indicated in Fig. 1, the string passes through the slot 18, bearing on 110

the second pulley or wheel 16 and out through the slot or recess 18.

The operation of this device is readily understood and merely comprises filling the 5 receptacle with chalk through the door 14, threading the line through the passage provided, and then holding the line at an inclination. The device will then travel along the inclined line due to gravity, the weighted 10 handle being provided to over-come the frictional resistance of the line and the pulley or wheel. By this means the line is chalked without the necessity of moving the device along the line manually, which is a manifest advantage to workmen, particularly in 15 dangerous places, such as in marking a roof for shingling, etc.

I also provide the loose wheel 19' having the grooved periphery, as shown, which is 20 adapted to ride or move on the cord in the receptacle portion of the device fitting between the sides thereof. This wheel or pulley 19' forms a weighted member holding the line in contact with the chalk at all 25 times. As it is free, it may ride on the cord when there is merely a small amount of chalk left in the receptacle or compartment.

It is therefore seen that I have provided 30 a device which is simple in construction and operation, being composed of few parts and easy to manipulate.

This application is filed as a continuation 35 of my prior application Serial Number 751,900 filed March 3, 1913, in so far as the subject matter is common.

What I claim is,—

1. A line chalker including a body portion and a handle portion, the latter being weighted, said body portion being formed 40 of two parts, one having a peripheral flange and partition flanges near each end thereof and the other being of the same conformation and fitting tightly against said flanges whereby a receptacle and a plurality of 45 compartments are formed, wheels mounted in said compartments, said partition flanges having openings therethrough in line with said wheels and said peripheral flange being cut away in alinement with said wheels to permit the passage of the line through the 50 device.

2. A line chalker including an elongated body portion and a weighted handle portion, said body portion being formed of two 55 parts, one having a flange extending entirely around the same, said flange being reduced at each end of the body part, and partition flanges extending from said first mentioned flange to the ends of said reduced flanges, the other part of said body portion being of the same conformation and fitting tightly against said first mentioned flange and having partition flanges corresponding to said first mentioned partition 60 flanges and also having flanges at the ends 65

corresponding to the reduced flanges at the ends of said first mentioned part, the two parts providing a receptacle and a plurality of compartments one at each end, wheels mounted in said compartments, said compartments and receptacle having a passage through them in alinement with said wheels for the line to be chalked.

3. A line chalker including an elongated body portion and a weighted handle portion, 75 said body portion being formed of two parts, one having a flange extending entirely around the same, said flange being reduced at each end of the body part, and partition flanges extending from said first 80 mentioned flanges to the ends of said reduced flange, the other part of said body portion being of the same conformation and fitting tightly against said first mentioned flanges and having partition flanges corresponding to said first mentioned partition flange and also having flanges at the ends 85 corresponding to the reduced flanges at the ends of said first mentioned part, the two parts providing a receptacle and a plurality of compartments one at each end, said reduced flanges on the first part and said flanges on the second part of said body portion terminating a slight distance apart to provide a slotted entrance into said compartments.

4. A line chalker including an elongated body portion and a handle portion, the latter being weighted, said body portion being formed of two parts, one having a peripheral flange and partition flanges near each 100 end of the body part and the other being of the same conformation and fitting tightly against said flanges whereby a receptacle and a plurality of compartments are formed, 105 wheels mounted in said compartments, said partition flanges having openings therethrough in line with said wheels and said peripheral flange being cut away in alinement with said wheels to permit the passage 110 of the line through the device, said peripheral flange being cut away to provide an opening into said receptacle, a door member therefor pivoted to one of said parts and a spring member normally holding said door 115 member shut.

5. A line chalker including an elongated body portion and a handle portion, the latter being weighted, said body portion being formed with a receptacle and separate compartments at each end, wheels mounted in each compartment, said body portion having a passage through said compartments and said receptacle in alinement with said wheels for a line to be chalked, and a loose 125 weighted member in said receptacle adapted to ride on the cord to force it into contact with the chalk.

6. A line chalker including two parts, one having a flange extending entirely around 130

the same, said flange being reduced at two places, partition flanges extending between said first mentioned flange and said reduced portions thereof, the other part having partition flanges corresponding to said first mentioned partition flanges and also other flanges corresponding to the reduced portions of said first mentioned flange, whereby a receptacle and a plurality of compartments one on each side thereof are provided,

wheels journaled in said compartments, said receptacle and compartments having a passage through them in alinement with said wheels to receive a line to be chalked.

In testimony whereof I affix my signature 15 in the presence of two subscribing witnesses.

BENJAMIN F. MILLS.
